COUNTER ROLLING MACHINE

Charles W. Bailey, Lynn, Mass., assignor to Stewart Bros., Inc. of Lynn, Lynn, Mass., a corporation of Massachusetts

Application December 29, 1937, Serial No. 182,284

7 Claims. (Cl. 12—65)

This invention relates to machines for rolling counter blanks to impart to them a rounded contour as a preliminary step in the molding process. The general objects of the invention are to improve machines of this class in efficiency and to increase their field of use by adapting them for the treatment not only of counter blanks, but of assembled quarter or quarter blanks of shoes, that is to say, the lined quarter or counter portion of the upper with or without an enclosed counter stiffener therein.

In one aspect the invention consists in a counter rolling machine having overhanging or open-end counter forming rolls so arranged that quarters having wings or other extensions thereon may be passed between the forming rolls without obstruction. The invention contemplates also the provision of corrugating or crimping rolls which may be employed for an auxiliary operation of crimping the lower edge of the counter or quarter when this is desired.

The invention includes within its scope an improved counter-concaving mold or cup for use in cooperation with the convex counter forming roll of the machine. The cup is provided with an extended concave face disposed substantially concentric with respect to the convex roll and acts to shape and iron the counter or other upper material as it is carried about the circumference of the roll. As herein shown I have reduced the frictional drag of the cup upon the material, and thus prevent objectionable distortion or stretching, by providing anti-friction means at spaced areas in the contour of the concave face of the cup. Such means may conveniently take the shape of concave rolls arranged with their surfaces substantially in the contour of the cup and spaced from each other by solid segments. The machine is thus adapted to handle a quarter of substantial thickness or one comprising outer and lining plies enclosing a fibre counter stiffener.

It has been found profitable to use stiffened quarters molded to shape in the manufacture of novelty shoes, sandals and strap sandals. In the manufacture of sandals, for example, it has been necessary heretofore to last the upper material chiefly to form the heel pocket or quarter section of the sandal. By the use of my invention it has now been made possible to eliminate the step of lasting strap sandals by providing preformed heel pockets which can be attached to the sole without the necessity of using lasts, thus considerably reducing the cost of production. In the past it has not been possible to accomplish this result

inasmuch as the wings of the quarters or straps could not be passed through the counter rolling machine. Furthermore, the solid molding cup which cooperates with the forming rolls was likely to stretch and distort the leather parts of the quarters.

To secure the foregoing objects, I have provided a machine wherein the forming rolls are disposed upon the free ends of adjacent shafts, the frame of the machine being shaped to make space for the wings of quarters passing between them. Moreover, the molding cup is furnished with freely turning rolls which eliminate the stretching or distortion of the leather parts of the quarters. As herein shown, the relative position of the rolls may be varied at will, and the upper roll may be yieldingly mounted so that it will compensate for variations in the thickness of the material being rolled.

These and other features of the invention will be best understood and appreciated from the following description of a preferred embodiment thereof, selected for purposes of illustration and shown in the accompanying drawings in which,

Fig. 1 is a view in front elevation of a counter rolling machine constructed according to my invention,

Fig. 2 is a view in side elevation of the machine shown in Fig. 1,

Fig. 3 is a view in detail of the cup,

Fig. 4 is a view in perspective of a counter assembled with the quarters of an upper after it has been operated on by the machine, and

Fig. 5 is a plan view of the counter rolling machine.

Before proceeding to a detailed description of the machine it will be convenient first to refer to its principal operating instrumentalities. These comprise oppositely driven cooperating rolls of which the roll 60 is convex in contour and the roll 58 concave in contour. The counter is passed into the bite of these rolls and thus given a preliminary curvature. It is carried about the rear side of the roll 60 and drawn over the concave face of a mold or cup having a concave face made up by the rolls 89, 90 and 91 and the solid segments 92, 94 and 96. The cup or mold is yieldingly and adjustably maintained in cooperative relation with respect to the convex roll 60.

A pair of geared crimping or corrugating rolls 108 and 112 provided with a guard are mounted in front of the rolls 58 and 60 and offset somewhat toward one side in position to engage the edge of the counter or quarter which is to be eventually flanged inwardly in the finished

- article. In the usual operation of the machine the flat counter blank or quarter is fed to the corrugating rolls with its lower edge against the face of the guard plate. As the blank leaves the corrugating rolls it passes to the forming rolls and is carried around by them emerging in the condition shown in Fig. 4, that is to say, with one edge crimped and having a pronounced curvature imparted thereto.
- Referring first to Figs. 1 and 5, it will be seen that the machine comprises a flat base 10 with spaced standards 11 and 12 which contain bearings for a horizontal driving shaft 13 upon which is keyed a driving pulley 14. Also keyed to the driving shaft 13 is a hand wheel 15; a loose pulley 16 is carried on the shaft 13 adjacent the driven pulley 14. Keyed on the shaft 13 near the inner end thereof is a pinion 17 in constant mesh with a large external gear 18 keyed to a horizontal main shaft 19 journalled in a bearing 20 disposed in the standard 11. The main shaft 19 is also journalled in a support 24 on the base 10. Carried on the shaft 19 adjacent the gear 18 is a small gear 26. Also on the shaft 19, between the bearing 20 and the support 24, is a pinion 28 which is constantly in mesh with a gear 30 keyed to a countershaft 32 journalled above the main shaft 19 in bearings 34 and 36. The bearings 34 and 36 are formed in rectangular blocks each of which is mounted in a guideway for vertical movement, the guideways being formed in the supports 24 and 11 and comprising vertical walls 54, 55, 56 and 57 and caps 38 and 40 bolted to the upper surfaces of the vertical walls. Helical compression springs 42 and 44 rest against the upper surface of the blocks 34 and 36 and the lower ends of the bolts 46 and 48 abut against washers 50 and 52 resting on the upper ends of the springs 42 and 44. The bolts 46 and 48 are threaded into the caps 38 and 40, and it will be apparent that the counter shaft 32 in its bearings 34 and 36 may be adjusted upwardly by pressure from beneath sufficient to overcome the downward force exerted by the springs 42 and 44. The tension may be varied by manipulation of the bolts 46 and 48.
- On the outer or overhanging end of the shaft 32 is keyed a concave forming roll 58 which fits over the curve of the convex forming roll 60 keyed to the end of the shaft 19. Surrounding the rear portion of the rolls 58 and 60 and integral with the support 24 is a rectangular frame 62 having a semi-circular recess in its end wall adjacent the bite of the rolls 58 and 60 and substantially concentric with the shaft 19 as shown at 64. Threaded through the back of the frame 62 are bolts 66 and 68, the inner ends of which abut against washers 70 and 72 seated against the outer ends of helical compression springs 74 and 76 which fit around lugs 78 and 80 on the rear wall 82 of a cup or mold 84. The cup 84 comprises a rectangular frame 86 in which are journalled freely turning concave rolls 88, 90, and 91. Integral with the frame 86 and disposed adjacent the roll 88 is a curved shield 92 having its upper surface substantially flush with the top of the roll 88. In the spaces between the rolls 88, 90 and 91 are segments 94 and 96, which have their upper surfaces substantially flush with the top of the rolls. The cup as a whole is designated by the reference character 84 and is disposed in the frame 62 as above explained so that the shield 92 lies directly behind the bite of the forming rolls 58 and 60. The rear wall 82 of the cup 84 is wedge-shaped so that the low-

er end of the cup extends farther forward than the upper end thereof. The surface of the cup 84 lying adjacent the forming roll 60 is curved to fit the contour thereof. Cylindrical lugs 98 and 99 integral with the frame 62 are disposed to abut against the upper and lower forward ends of the cup 84 and limit the position of the cup 84.

Bolted to the standard 24 is a frame 100 which carries the bearing 101 for a counter shaft 102. The inner or right hand end of the counter shaft 102 is journalled in a removable bearing 104 secured to the standard 11 of the frame. Adjacent to the bearing member 104 and on the counter shaft 102 is a gear 106, secured to the counter shaft by a screw 105 in an integral hub 107, and in mesh with the gear 26. On the other end of the shaft 102 is an upper toothed corrugating roll 108, the latter being located opposite to the inner ends of the forming rolls 58-60. In mesh with the roll 108 and mounted for rotation about a stud 110 is a lower corrugating roll 112. The stud 110 is rigidly mounted in a yoke 114 pivotally mounted to the frame 100 on a pivot pin 118. A set screw 116 holds the stud 110 against rotation. A helical compression spring 120 bears against the bottom of the yoke 114, and a washer 121 seats against the lower end of the spring 120 to form an abutment for a bolt 122 threaded through a lug 124 made integral with the frame 100. The frame 100 is adjustable horizontally inasmuch as the attaching bolts 126 pass through elongated slots in the frame 100 and thus the width of the corrugated margin of the counter may be adjustably controlled.

In front of the frame 100 is a safety guard and gauge unit comprising converging plates 132 and 133, located just in front of the bite of the rolls 108 and 112, and a vertical gauge plate 134. The space between the adjacent ends of the plates 132 and 133 is small enough to prevent the entrance of a human finger. The guard is bolted to the frame 100 by the bolts 130 which work in elongated horizontal slots in the guard 128. By loosening the bolts 130 and shifting the unit the gauge may be adjusted horizontally and the transverse position of the counter with respect to the forming rolls thus adjustably controlled. It will be noted that the corrugating rolls and the gauge plate 134 are located substantially opposite to the inner ends of the forming rolls and that the gauge is engaged by that edge of the counter or assembly counter blank which is to be lowermost when incorporated in the finished shoe.

The machine may be operated by hand by utilizing the hand wheel 15 or may be driven by a belt encircling the driving pulley 14. In either case, when power is applied the shaft 13 rotates and causes rotation of the lower convex forming roll 60 through the pinion 17 and the gear 18. Similarly the upper forming roll 58 is caused to rotate by the shaft 13 through the pinion 17, the gear 18, the pinion 28, the gear 30 and the shaft 32. At the same time the gear 26 on the main shaft 19 causes the upper corrugating roll 108 to rotate, the power being transmitted through the gear 106 and the counter shaft 102. A counter is fed between the corrugating rolls 108 and 112 with its lower edge against the gauge plate 134. Subsequently the counter is automatically fed between the forming rolls 58 and 60 which impart to it a rounded contour. After the counter has passed between the bite of the rolls 58 and 60 it is pressed against the rear portion of the

roll 60 by the cup 84, the friction rolls 89, 90, and 91 serving to ease the path of the counter between the roll 60 and the cup 84 while the shield 92 deflects the counter between the cup 84 and the roll 60. When it is desired to roll counters enclosed in quarters a similar operation is performed by the machine, with the exception that the effective distance between the rolls 58 and 60 is widened by reducing the pressure exerted by the springs 42 and 44 (by loosening the bolts 46 and 48). Similarly the bolts 66 and 68 are loosened to reduce the pressure exerted by the springs 74 and 76 against the back of the cup 84. Furthermore, the bolt 122 is loosened to reduce the pressure exerted by the spring 120 against the yoke 114 which actuates the lower corrugating roll 112. Having thus increased the clearances between the operating elements of the machine, it is possible to pass through the machine a counter enclosed between the upper and lining of the quarter section of a shoe. The result is shown in Fig. 4, where it will be seen that the corrugating rolls 108 and 112 act upon the lower margin of the assembled quarters and counter and that a pronounced curve has been imparted to the entire assembly. The curve shown in Fig. 4 is a trifle exaggerated, a fact necessitated by space limitations in the drawings. The assembled shoe parts may be used in the construction of shoes after the unit has been curved and crimped or corrugated as shown in Fig. 4 or it may be molded, prior to being assembled with the other elements in the shoe, so that the corrugated portion of the margin is bent inwardly to form a flange destined to rest upon the bottom of the last. In machines heretofore used it would be impossible to roll an assembly such as that shown in Fig. 4 for the reason that the extending wings 136 would become damaged between the frame of the machine and the forming rolls or caught in the bearings for the forming rolls shafts, since it has been the practice to mount the forming rolls between bearings rather than on free ends of the shafts.

It will now be apparent that I have provided a machine which produces a result long sought after by those skilled in the art. Such persons will readily appreciate the fact that numerous variations from the structure disclosed above will be possible and practical. However, the above description merely relates to one preferred embodiment of the essential concept underlying my invention, and it should be understood that the scope and spirit of the invention is limited only by the extent of the appended claims.

I claim:

1. In a counter rolling machine the combination of corrugating rolls, forming rolls, and a cup disposed behind said forming rolls and including a shield, a plurality of freely turning rolls, and a plurality of stationary segments.
2. A cup for a counter rolling machine, comprising a bodily movable unit including a backing frame, a plurality of freely turning rolls, journaled in said frame in an arcuate pattern, a plurality of segments disposed in said cup and having their surfaces substantially flush with the surfaces of the rolls, a shield on one end of

said frame adjacent one of said rolls and yielding means for pressing the unit into operative position.

3. A counter rolling machine, which comprises a main shaft, and two adjacently disposed countershafts, all three shafts being supported by bearings spaced from their ends, a convex roll on the end of said main shaft and a concave roll carried on the end of the one countershaft and disposed adjacent said convex roll; an upper corrugating roll on the end of the second countershaft, a stud disposed below said second countershaft, a lower corrugating roll disposed for rotation about said stud, and an adjustably mounted cup disposed behind said convex and concave rolls and comprising a plurality of freely rotating rollers and solid segments arranged in alternating series.

4. A machine for rolling counters and the like, which comprises a pair of corrugating rolls, an adjustable work guide and safety guard disposed before said corrugating rolls, convex and concave forming rolls disposed behind said corrugating rolls, and a curved cup cooperating with said forming rolls, means for regulating the distance between said corrugating rolls, means for varying the distance between said forming rolls, and means for controlling the distance between said forming rolls and said cup.

5. A counter rolling machine which comprises a base, a frame in said base, a plurality of bearing standards integral with said base, a driving shaft journaled in two of said bearing standards, a pinion on said driving shaft, a main shaft supported by two of said bearing shafts and having one end free, a gear on said main shaft in mesh with said pinion, a countershaft supported for limited upward movement by two of said bearing standards and having one end free, a spur gear on said main shaft, a gear on said countershaft in mesh with said spur gear, a convex roll in the free end of said main shaft, a concave roll on the free end of said countershaft, a pair of corrugating rolls driven by gearing from said main shaft, and a cup disposed in said frame adjacent said convex and concave rolls and having a plurality of freely turning rolls and stationary segments adjacent said rolls.

6. In a machine for forming shoe counter blanks having projecting wings, cooperating forming rolls supported in open-ended relation, a spring pressed forming cup having spaced anti-friction rolls therein associated with the forming rolls and arranged to yield bodily to accommodate variation in thickness of the blanks, and a gauge located in position to line the lower edge of the blanks with the inner ends of the forming rolls while the wings of the blanks are free to pass beyond the outer ends of the rolls.

7. In a machine for forming shoe counter blanks and including driven convex and concave forming rolls, a forming unit comprising a frame having alternate anti-friction rolls and curved spacing segments therein, and means for supporting the unit for bodily yielding retracting movement in the machine with respect to the convex forming roll.

CHARLES W. BAILEY.
